UNITED STATES PATENT OFFICE.

RICHARD A. ANTHONY, OF NEW YORK, N. Y., ASSIGNOR TO THE E. & H. T. ANTHONY & COMPANY, OF SAME PLACE.

PHOTOGRAPHIC-PLATE HOLDER.

SPECIFICATION forming part of Letters Patent No. 439,808, dated November 4, 1890.

Application filed March 6, 1890. Serial No. 342,898. (No model.)

To all whom it may concern:

Be it known that I, RICHARD A. ANTHONY, a citizen of the United States, and a resident of New York, in the county of New York and 5 State of New York, have invented certain new and useful Improvements in Photographic-Plate Holders, of which the following is a specification.

My invention relates to improvements in 10 plate-holders for photographic apparatus; and it consists in a new and effective construction of the slide-locking devices, whereby they are firmly held in the plate-holder until their removal is desired.

15 In the drawings the same reference-letters indicate the same parts in all the figures.

Figure 1 is an elevation of the front of a double plate-holder having my slide-lock attached, the slide on the side presented to 20 view being removed. Fig. 2 is an edge view of the parts shown in Fig. 1. Fig. 3 is an end view of the plate-holder, both of the slides being in their closed position and locked therein by the slide-lock. Fig. 4 is a view the same 25 as Fig. 3, the slide-lock being unlocked for the removal of the lower slide.

It will be obvious that although I show my improvements as applied to a double plate-holder, it may be equally well employed in 30 single holders.

A is the frame of the plate-holder. It may be constructed in any preferred manner.

B B are the slides.

D is the usual diaphragm, (or the back of 35 the holder if it be a single plate-holder.) It is provided with the usual spring E for pressing the plate forward. These parts are or may be made in any preferred form.

F is my improved lock for the slides, which 40 I have found much more effective, simple, and convenient than any heretofore known to me. The lock proper comprises a screw or equivalent pivot G, which is fastened in the end of the frame of the holder. It passes through a 45 hole made in the foot or base H of the lock and the lock swivels on it. A spring I, abutting against the head of the pivot G at one end and pressing against the base H at the other end, puts the lock under spring-friction, so that it

will remain in any position in which it is left. 50 Any other suitable means may be employed for securing this result. The upper part of the lock is provided with a plate or bar J, terminating at each end in lateral projections K K, which are preferably provided with thumb- 55 pieces L L, whereby the lock can be easily swung or turned on its pivot. The construction and dimensions of the parts of the lock are such that it will ordinarily engage with the ends of both of the slides, and they can 60 only be withdrawn when the lock is intentionally placed in the position shown in Fig. 4. When so placed, it is obvious that the lower slide can be withdrawn, and of course when swung into directly the reverse position the 65 upper slide can be withdrawn.

It will be observed that I cut away the projecting part M of the slides, which are grasped by the finger and thumb for their withdrawal from the holder at one side of each slide, and 70 that the projecting parts which I leave are upon opposite sides of the slides. This I do so that the projection M on one slide may not interfere with the finger or thumb of the operator when desiring to withdraw the other 75 slide from the holder and when manipulating the slide-lock.

I do not limit myself to the precise details of construction of the parts as shown and described, because it will be obvious to those 80 who are familiar with this art that various modifications may be employed and still the essentials of my invention be present.

I claim—

1. A plate-holder provided with a slide-lock 85 eccentrically pivoted to the plate-holder and adapted to have a rotary movement only relative to its pivot and to be successively engaged with and disengaged from the ends of the slides by simply turning on its pivot, the 90 relation between the lock and the plate-holder being such that no part of the lock at any time projects beyond the sides of the plate-holder, substantially as set forth.

2. A plate-holder provided with a friction-held slide-lock eccentrically pivoted to the plate-holder and adapted to have rotary movement only relative to its pivot and to be suc-

cessively engaged with and disengaged from the ends of the slides by simply turning on its pivot, the relation between the lock and the plate-holder being such that no part of the lock at any time projects beyond the sides of the plate-holder, substantially as set forth.

5 Signed at New York, in the county of New

York and State of New York, this 28th day of February, A. D. 1890.

RICHARD A. ANTHONY.
